[57] CLAIM

The ornamental design for a recliner chair tray, as shown and described.

DESCRIPTION

FIG. 1 is a front perspective view of our new recliner chair tray;

FIG. 2 is a bottom perspective view of the recliner chair tray of FIG. 1;

FIG. 3 is a front perspective view of our new recliner chair tray showing the lounge chair environment in dashed lines, which dashed line portions form no part of my invention; FIG. 4 is a view taken from the rear of our new design of FIG. 1;

FIG. 5 is a front view of our new design of FIG. 1;

FIG. 6 is a side view of our new design of FIG. 1, with the other side being the same;

FIG. 7 is a bottom plan view of the recliner chair tray of our FIG. 1; and,

FIG. 8 is a top plan view of our FIG. 1.

The broken lines in FIGS. 1 and 8 are for environmental purposes only and form no part of the claimed design.
